US00D926067S

(12) **United States Design Patent** (10) **Patent No.:** **US D926,067 S**
(45) **Date of Patent:** **** Jul. 27, 2021**

(54) **DOORBELL**

(71) Applicant: **GOOGLE LLC**, Mountain View, CA
(US)

(72) Inventors: **Rochus Emanuel Jacob**, San Francisco, CA (US); **Hae rim Jeong**, San Francisco, CA (US); **Adam Duckworth Mittleman**, Redwood City, CA (US); **Shih Ming Tsung**, New Taipei (TW); **Jacobi Colton Grillo**, San Francisco, CA (US); **Jason Evans Goulden**, Los Gatos, CA (US); **Étienne Bérubé**, San Francisco, CA (US); **Minjung Kim**, Sunnyvale, CA (US)

(73) Assignee: **GOOGLE LLC**, Mountain View, CA
(US)

(**) Term: **15 Years**

(21) Appl. No.: **29/759,449**

(22) Filed: **Nov. 23, 2020**

Related U.S. Application Data

(63) Continuation of application No. 29/694,544, filed on Jun. 11, 2019, now Pat. No. Des. 906,149, which is a continuation of application No. 29/649,733, filed on Jun. 1, 2018, now Pat. No. Des. 879,640, which is a continuation of application No. 29/609,547, filed on Jun. 30, 2017, now Pat. No. Des. 830,872.

(57) **CLAIM**

The ornamental design for a doorbell, as shown and described.

DESCRIPTION

FIG. 1 is a front perspective view of a doorbell showing our new design;

FIG. 2 is a rear perspective view thereof;

FIG. 3 is a front elevational view thereof;

FIG. 4 is a rear elevational view thereof;

FIG. 5 is a right-side elevational view thereof;

FIG. 6 is a left-side elevational view thereof;

FIG. 7 is a top plan view thereof; and,

FIG. 8 is a bottom plan view thereof.

The broken lines illustrate structure or features that form no part of the claimed design.

1 Claim, 7 Drawing Sheets
